UNITED STATES PATENT OFFICE.

EDGAR W. WILSON, OF DENVER, COLORADO, ASSIGNOR OF TWO-THIRDS TO
WILLIS Z. BILLS, OF SAME PLACE.

COMBINATION-LOCK.

SPECIFICATION forming part of Letters Patent No. 448,175, dated March 10, 1891.

Application filed January 26, 1888. Serial No. 261,939. (Model.)

To all whom it may concern:

Be it known that I, EDGAR W. WILSON, a citizen of the United States, residing at Denver, in the county of Arapahoe and State of Colorado, have invented certain new and useful Improvements in Combination Door-Locks, of which the following is a specification, reference being had therein to the accompanying drawings, in which similar letters refer to corresponding parts.

My invention relates to combination door-locks; and the object of my improvements is to provide a lock which may be easily and quickly locked or unlocked by means of keys contained in the outside door-knob and can also be easily and quickly changed from a combination-lock to a night-lock or to a simple door-latch by means of screws attached to the inside knob-plate. This I attain by means of the mechanism shown in the accompanying drawings, in which—

Figure 1 is a sectional view of my combination door-lock attached to a door, showing the knob-bolt broken off and the different parts of the outside knob disconnected, also showing a transverse section of the latch-bolt and the stirrup in which the same works and a transverse section of a portion of the door. Fig. 2 is a sectional view of the outside knob, showing two of the keys. Fig. 3 is a back view of the outside knob, showing the holes in which the front ends of the keys are inserted. Fig. 4 is a front view of the shank or neck of the outside knob, showing the holes in which the rear ends of the keys are inserted. Fig. 5 is a front view of a tumbler or notched ring, showing a spring attached to the same. Fig. 6 is a front view of a sleeve-tumbler. Fig. 7 is a back view of the outside sleeve knob-plate, showing a spring attached to the same. Fig. 8 is a view of a portion of the latch-bolt, showing the dog and coil-spring around said bolt, and a transverse section of the knob-bolt and the connecting flange-sleeve. Fig. 9 is an inside view of the inside knob-plate and flange of the flange-sleeve.

As represented in the drawings, A is the outside knob, which is made stationary on the knob-spindle F and provided with key-holes

a and small pin-hole a'. Knob A is also made hollow, so as to inclose the sleeve-tumbler C and the tumbler D, and in the back part of which is fitted the shank or neck of the knob. Shank B is provided with key-holes b and pin b' and is made to fit over and revolve around the sleeve portion of knob-plate E. Sleeve knob-plate E is made stationary on the door L in any suitable manner and is provided with spring E', spring E², and pin E³, as shown in Fig. 7.

C is a sleeve-tumbler provided with notches C' and slot c. The sleeve portion of said tumbler C is made to fit and revolve around knob-spindle F and inside the sleeve of knob-plate E.

D is a tumbler provided with notches D' and D², slot d, and spring d' and its attachment d².

F is the knob-spindle, to which is attached the outside and inside knobs, and provided with pin f.

G is the connecting flange-sleeve, through which knob-spindle F passes and around which it revolves, and is made to connect with the sleeve of tumbler C by means of pin g. The flange part of sleeve G is adjustably attached to inside knob-plate J by means of screw j and set-screw j'.

H is the latch and lock-bolt, provided with coil-spring h' and dog h, to engage with pin f on the knob-bolt.

I is any suitable stirrup made to retain spindle F in its proper position, and through which bolt H is free to move endwise and the sleeve or flange G is free to revolve.

K is the inside knob; L, the door, and O the keys.

In the operation of my improved combination door-lock, when it is desired to use the same as a latch only, flange-sleeve G is pulled out to the position shown in Fig. 1 and the tumblers with it by means of screw j, in whose spiral groove is arranged the upper edge of the flange of said sleeve G, the shoulders g² and g³ of flange-sleeve G being so arranged as not to interfere with or raise dog h, but allow the same to come in contact with pin f when either of the knobs are turned, and un-

latching the door. When it is desired to lock the door so that it cannot be unlocked, even with the combination, flange-sleeve G is pushed in by turning the screw *j* and moving set-screw *j'* to the end J' of slot J², (which slot is shown by dotted lines in Fig. 9,) and fastening the flange-sleeve in that position with the set-screw, by means of which pin *f* is thrown to and held in that part *g'* of the slot in sleeve G shown in Fig. 8, when shoulder *g*² raises up dog *h*, so that pin *f* cannot come in contact with said dog, latch-bolt F thus becoming a lock-bolt, spring *h'* bearing against dog *h* and keeping the same thrown out and the door locked.

When it is desired to use the lock with the combination, the flange-sleeve G is pushed in by screw *j*, the flange turning round to its proper position, so that set-screw *j'* is near the end J³ of slot J² and pin *f* is in that portion *g'* of the slot in sleeve G, so that when keys O are all in the position, as shown in Fig. 2, knob A or K being turned without turning tumblers C and D, *b* does not turn sleeve G, while bolt F turns, causing pin *f* to come in contact with dog *h*, throwing bolt II back and unlocking the door; but when keys O, or any one of said keys, are pushed in, the webs O' and O², being inserted in notches C' of tumbler C and D' of tumbler D, cause said tumblers to turn with the knobs, and the sleeve of tumbler C, being connected with sleeve G by pin *g*, also turns said sleeve G, causing shoulder *g* to come in contact with and raise dog *h* before pin *f* comes in contact with said dog, thus preventing the bolt H from being thrown back, allowing the door to remain locked. Pin *b'* is made stationary in shank B and inserted through slot *c* of tumbler C and slot *d* of tumbler D and into hole *a'* of knob A for the purpose of turning shank B with knob A and not allowing tumblers C and D to revolve around bolt F any farther than from one end to the other of said slots, and also to prevent knob A from being unscrewed. Spring *d'*, (shown in Fig. 5,) attached at one extremity to tumbler D and at the other extremity to sleeve E by small pin *e*, and spring E', (shown in Fig. 7,) attached at one extremity to sleeve knob-plate E by spring attachment E² and at the other extremity to the sleeve of tumbler C by means of pin *c'*, are for the purpose of keeping the notches D' of tumbler D and C' of tumbler C in line when the knobs are not being turned, so that the webs of the keys may be inserted through said notches. Pin *f* on bolt F, striking against shoulder *g*⁵ of flange sleeve G, prevents the knobs from turning any farther in that direction. When it is desired to change the combination, the inside knob K is unscrewed from the bolt F sufficiently to allow knob A to be freed from the pin *b'*, when said knob A can also be unscrewed from bolt F and the keys O turned over, reversing their position from that shown in Fig. 2, it becoming necessary then to push the keys in to unlock the door. Keys O may also be placed so that it may be necessary to push each alternate key in and the others out to unlock the door, or changed and made more or less complicated, according to the number of keys, which may be any number. Notches D² of tumbler D are for the purpose of keeping the keys from being pushed in or out when the knobs are being turned.

Having thus described my invention, what I claim, and desire to secure by Letters Patent of the United States, is—

1. In a combination door-lock, knob A, screwed on spindle F and provided with shank B, sleeve knob-plate E, tumbler D, and sleeve-tumbler C, made to connect with flange-sleeve G, spindle F, provided with pin *f*, and bolt II, provided with dog *h*, for the purpose set forth and described.

2. In a combination door-lock, knob A, provided with shank B, sleeve knob-plate E, sleeve-tumbler C, tumbler D, and keys O, for the purpose set forth and described.

3. In a combination-lock, the bolt II, having pivoted dog *h* and spiral spring *h'*, in combination with the spindle F, having pin *t*, and the sleeve G, having the slot *g'* and shoulders *g*² *g*³, as and for the purpose set forth.

4. The combination, in a permutation-lock, with the knob-spindle thereof, of a sliding sleeve G and tumbler C, the two interlapping at their meeting ends and connected by a pin *g*, as shown and described.

5. The combination, in a permutation-lock, with the knob-plate J and flanged sliding sleeve G, slotted at *g*², of the swiveled screw *j* and set-screw *j'*, arranged as shown, whereby the sleeve G may be set in a suitable position and then moved, as and for the purpose specified.

6. In a combination door-lock, the combination of knob A, attached to spindle F and provided with sleeve knob-plate E, shank B, tumblers C and D, and keys O, shank B being provided with pin *b'*, tumbler D being provided with notches D' and D² and slot *d*, and sleeve-tumbler C being provided with notches C', slot *c*, and pins *c'* and *g* and made to connect with flange-sleeve G, spindle F, provided with pin *f*, and bolt II, provided with dog *h* and spring *h'*, and knob-plate J, provided with screw *j*, set-screw *j'*, and slot J², for the purpose set forth and described.

7. In a combination door-lock, the combination, with knob A, attached to spindle F and inclosing adjustable and reversible keys O, and sleeve-tumbler C, provided with spring E, attached to the same by means of pin *c'*, of tumbler D, provided with spring *d'*, attached to the same by means of spring attachment *d*², shank B, fitted into the back part of said knob and provided with pin *b'*, and sleeve knob-plate E, to which also are

attached the springs E' and d' by means of the spring attachment E^2 and pin e and provided with pin E^3 , flange-sleeve G , provided with shoulders g^2 , g^3 and g^5 and adjustably attached to knob-plate J by means of screw j and set-screw j' , knob-plate J , provided with slot J^2 , pin f , made stationary on bolt F , and dog h , pivoted to bolt H , for the purpose set forth and described.

EDGAR W. WILSON.

In presence of—

LOGAN RUSSELL,
F. D. RUSSELL.
